HYDRAULIC PRESS IN WHICH THE THRUST
OF THE RAM AND THE REACTION OF THE
SLIDE BAR ARE EQUALIZED

Alois Karl Nowak, Evanston, Ill.

Application August 21, 1947, Serial No. 769,913

5 Claims. (Cl. 100—71)

1. In the manufacture of electrical instruments, cash registers, typewriters, clocks, and the like, millions of small sheet metal stampings are made in mechanical presses driven by cranks or eccentrics and known to the trade as "inclinable presses," "open back presses," and "open back inclinable presses." In spite of the fact that those presses have many well known inherent defects and shortcomings, they are still in conventional use. The object of this invention is to replace them with a hydraulic press that will overcome their defects and shortcomings and provide:

1. An arrangement whereby the force exerted by the driving mechanism of the press is limited to a predetermined amount to prevent breaking the press when two work pieces are fed into the press, or the press is over-adjusted.

2. An arrangement whereby the press may be given a dwell for a minute interval at the bottom of the stroke without increasing the time of the stroke cycle, and to improve the fineness of the contours in the article made.

3. An arrangement whereby the force exerted by the press head is continually indicated by a gauge and provisions are made to sensitively maintain, raise or lower, this force without interrupting production.

4. For replacing the conventional adjusting screws used in mechanical presses with means that will permit most sensitive adjustment of the "shut height," either up or down, while the press is operating and without interrupting production.

5. For replacing the present conventional clutch mechanism for starting and stopping the press with means having no parts subject to wear or severe shocks; and

6. An arrangement whereby the face of the press head and the face of the bed remain parallel without distortion while the press is exerting the maximum pressure.

Other objects and advantages of the invention will appear as the disclosure proceeds and the description is read in connection with the accompanying drawings, in which

Fig. 1 is a diagrammatic vertical section through a press embodying the invention, parts being shifted in position to make them appear in a single figure of the drawings;

Fig. 2 is a diagrammatic vertical section through a control valve showing the parts in the positions they assume when it acts as a safety valve;

Fig. 3 is a similar view showing the parts in the positions they assume in replenishing the fluid in the system;

Fig. 4 is a similar view showing the parts in the positions they assume when the control valve is used to start or stop the press head;

Fig. 5 is an enlarged section through the control valve and associated parts;

Figs. 6 and 7 are transverse sectional views taken on the lines 6—6 and 7—7, respectively, of Fig. 1;

Fig. 8 is a somewhat diagrammatic section of one form of valve used in controlling the press by means of air pressure;

Fig. 9 is a diagrammatic elevation showing an alternative form of means for varying the volume of fluid in the system;

Fig. 10 is a longitudinal sectional view through a manually operated valve for controlling the operation and showing the parts in position to adjust the press head downwardly;

Fig. 11 is a similar view showing the parts in neutral or normal position; and

Fig. 12 is a similar view showing the parts in the position they assume for adjusting the press head upwardly.

But these drawings and the corresponding description are used for the purpose of disclosure only, and are not intended to impose unnecessary limitations on the claims.

The frame is preferably fabricated from structural elements by welding and includes a bed 1 and side plates 2 and 3. A motor 4 on top of the frame drives a belt 5, which in turn drives a flywheel 6 keyed to shaft 7 having its bearings 8 in the side plates 2 and 3 (Fig. 7). Between those plates an eccentric 9 is keyed to the shaft 7 and fitted with an eccentric strap 10 by means of which it reciprocates a fixed stroke plunger 11 guided in a hydraulic cylinder 12 having its walls bronze lined and its lower end provided with a stuffing box and packing.

The cylinder 12 is part of a fixed assembly with intermediate bracket or block 13 and hydraulic working cylinder 14. The assembly may be made in a one-piece casting or in three parts fastened together by suitable means. The assembly is mounted between the plates 2 and 3 of the frame upon a large pin 15 having bearings 16 (Fig. 6). Lock plates 17 prevent the pin from turning, and the assembly is secured in place on the pin by a key 18.

The axis of the pin 15 is midway between the axes of the cylinders 12 and 14. The upper ends of the cylinders are closed, and adjacent to their upper ends they are connected by a single pipe 19.

The working cylinder 14 has within it a working plunger 20 of exactly the same diameter as the

driving plunger 11 in the cylinder 12. In consequence, the two plungers 11 and 20 have the same cross sectional area, and hence the same displacement. The two cylinders 12 and 14 and their connecting pipe 19 form a closed hydraulic system, and the fixed stroke and displacement of the plunger 11 in cylinder 12, mechanically actuated by eccentric 9, will cause identical displacement in cylinder 14 and identical stroke of the plunger 20 and the press head 21.

It is axiomatic in hydraulics that the pressure in every part of a closed system is the same. The force exerted by a hydraulic plunger is the cross sectional area of the plunger multiplied by the pressure per square inch. Therefore, the force of plunger 11 is the same as plunger 20; and, since these two plungers are equi-distant from the axis of the pin 15, the two forces balance each other. The pin is consequently subjected to a vertical upward acting force equal to the sum of the two forces. By strengthening the bearings 16 of pin 15 with heavy bars 22 (Fig. 6), welded to the side plates 2 and 3, and extending them to their lower ends, distortion of the side plates is completely eliminated, and the guides 23 of the press head 21 are maintained in precise alignment.

On top of the cylinder 14 is an air cylinder 24 with its piston 25 and crosshead 26. Two pull-back rods 27 are fastened to the crosshead, and support on their lower ends the ears 28 of the press head 21. Air cylinder 24 is supplied by pipe 29 with air pressure of 70 pounds per square inch, giving its piston 25 a continuous tendency to remain in its upper position, and hence the press head is continuously pulled upward.

During the down stroke of plunger 11, the air piston 25 can raise the press head 21 and plunger 20 only at the rate at which the down movement of the plunger 11 permits the filling of the cylinder. Thus, the movement of plunger 20 and press head 21 is perfectly harmonious, the beginning and end of the upper and lower ends of the stroke gradually approaching zero velocity from the maximum at midstroke.

The air pipe 29 is supplied with a check valve 30 to prevent air flow out of the air cylinder 24, and thus causes intensification of the air pressure in the cylinder due to the additional compression effected by the down movement of the piston 25. The construction of the air cylinder 24 and the piston 25 is such as to limit this additional compression to a ratio of 2:1. Thus, the air pressure at the bottom of the stroke will be approximately 140 pounds per square inch, which is desirable to effect the stripping of the work from the die.

It will be apparent from the description that the working plunger and the press head have exactly the same reciprocating stroke as the driving plunger 11.

Adjustment of the press head

Working practice, however, demands an adjustment of the press head 21 up or down for various heights of die sets placed between press head 21 and press bed 1. It is an important feature of this invention that the adjustment of the press head may be effected by varying the volume of fluid in the closed hydraulic system consisting of the cylinders 12 and 14 and the connecting pipe 19. Increasing the fluid in the system will lower the press head, and decreasing the fluid in the system will raise it, and by control of the increase or decrease an exceedingly fine adjustment may be had.

An auxiliary motor 31 drives a small pump 32 having its intake connected by pipe 33 with an overhead tank 34 (Fig. 1). A discharge pipe 35 of the pump is divided into two branches 36 and 37. The branch 36 is equipped with a check valve 38, and leads directly to the upper end of the cylinder 12. The check valve permits flow away from the pump to the cylinder but checks any tendency to flow in the reverse direction. The branch 37 is fitted with a globe valve 40 and is connected to the pipe 33. By opening the valve 40, the pump will discharge through the pipes 35, 37, and 33 back into the tank while the check valve 38 prevents any flow of fluid through the pipe 36 from the cylinder 12.

A pipe 41, fitted with a globe valve 42, connects the branch pipes 36 and 37, so that by opening the valve 42 fluid may escape from the cylinder 12 through the port 39, pipe 36, pipe 37, and pipe 33 to the tank. Another pipe 43 parallel to the pipe 41 is connected to the pipes 36 and 37 and fitted with a pressure release valve 44. In the event the pump 32 is running and the valves 40 and 42 are closed, the pump discharge will pass through the pipe 35, check valve 38, pipe 43, through relief valve 44 into pipes 37 and 36, and thence to the tank 34.

It will be apparent from this arrangement that the volume of fluid in the closed hydraulic system can be changed at will, even when the press is operating; that is, the main motor driving the eccentric and both plungers 11 and 20 reciprocating. By closing valve 40 and opening valve 42, the distance between the bed 1 and the working face of the press head 21 (when the press head is at the bottom of the stroke) will increase. By closing valves 40 and 42, that distance will decrease. By closing valve 42 and opening valve 40, the distance will remain fixed.

If some operation to be performed on the press requires a gradual but continuous approach of the press head 21 toward the press bed 1 at the end of each stroke, that may be readily accomplished by continuous discharge of the pump 32 into the hydraulic system. During each stroke, the pump delivers a fixed amount of fluid into the cylinder 12, and the following stroke will thus be advanced toward the bed by that amount.

Fixing the adjustment of the press head

In conventional stamping operations for which this press is primarily intended, this distance, which is called in the trade "shut height," is fixed for a given die set and product. The press head is adjusted for the required shut height, and is then fixed for the production run with this die set.

With the stuffing boxes of the cylinders 12 and 14 absolutely tight and no leaks whatever in the communicating pipe 19, the volume of fluid would remain the same, and consequently the shut height would remain the same. The adjustment of the system above described would therefore be sufficient to accomplish the desired result. However, in actual practice the packing in the stuffing boxes wears, and gradually increasing losses of fluid will result. And any loss of fluid, no matter how minute, will increase the shut height, and thus impair the resulting product and require the continuous attention of the operator to re-establish and maintain the required shut height. It is an important feature of this invention to maintain the shut height automatically.

Adjustable stop sleeves 45 (Fig. 1) have their

lower portions enlarged and drilled to receive pins for turning them. The upper portions are threaded on the outside and screwed into the ears 46 of cylinder 14. Jam nuts 47 are provided to prevent any change in the position of the stop sleeves 45 after the adjustment has been made. Pull back rods 27 pass through and are guided by the stop sleeves 45.

When the shut height of a given die set has been adjusted hydraulically with the pump 31 and the valves 40 and 42, the stop sleeves are then set in such a manner that the upper surfaces of the ears 28 of the press head 21 just contact the lower surfaces of the stop sleeves when the press head 21 is at the end of its up stroke. The jam nuts 47 are then tightened to make this setting permanent. Such a fixed setting will make the volume of the hydraulic system permanent, and any leakage of fluid during any stroke of the plunger 11 will produce a vacuum in the system which will automatically cause the control valve 48 to replenish the lost liquid.

The control valve

The control valve 48, shown in the large section (Fig. 5), is mounted on top of the cylinder 12, which is open to give access of the fluid to the valve. The control valve casing includes a heavy flange 49, a valve seat 50 which guides and seats the hollow valve body 51, the upper portion of which is threaded for screwing on the sleeve 52, and the upper part of the sleeve is also threaded for screwing into the spring plate 53. This assembly is enclosed in casing 54 having a lower flange which, together with the heavy disk 49, is secured to the cylinder 12 by bolts 55.

Superimposed on the valve casing 54 in perfect alignment with it is an air cylinder 56 with an air piston 57 and closing cap 58 provided with a port 59. The air cylinder below the piston 57 has a port 60. Fastened to the air piston 57 by means of a bolt 61 is a packing cap 62, which is tightly threaded into a hollow stem 63 confining and compressing packing 64. The lower part of the stem 63 is guided in the spring plate 53 and abuts against the upper surface of the sleeve 52. A spring 65 is placed between the valve seat 50 and the spring plate 53.

The lower part of the air cylinder 56 contains a stuffing box for the hollow stem 63 consisting of a gland ring 66, bronze guides 67, and compression packing 68. This stuffing box safely separates the air cylinder 56 from the valve housing and prevents any possible leakage between the two.

Placed in the center of the hollow valve 51, sleeve 52, and hollow stem 63 is a small valve 70 seating on the valve part 51 and extending upward as stem 71 is slightly enlarged to form a piston 72, which is lapped into the hollow part 63 forming a fluid seal. Below the piston head 72 is a washer 73. Between this washer 73 and the valve part 51 is a spring 74. The valve 70, stem 71, and piston head 72 have a continuous hole 75 for transferring the fluid pressure within the cylinder 12 to above the piston head 72. The valve 70 has directly under its seat the relieved section 76, which coincides with a drilled port 77 in the valve 51.

The control valve serves several purposes

The control valve 48 serves a triple purpose. First, it will act automatically as a safety valve, protecting the press against overloading; second, as a filling valve for replenishing lost fluid from

the system; and, third, by manual operation it can be used to start and stop the press head. The positions of the parts in those three operations are shown in Figs. 2, 3, and 4.

The control valve as a safety valve

The hydraulic system of the press may be designed for a maximum pressure—for example, 3,000 pounds per square inch. If that pressure is reached in the hydraulic system, it will be exerted through the hole 75 in the valve 70 to above the piston 72. That piston has a slightly larger area than the seated area of valve 70. This difference in area, multiplied by 3,000, gives the total force on the piston head 72 tending to force the valve 70 off the seat 51. The spring 74 is made to balance that force. Should the pressure of 3,000 pounds per square inch be exceeded, the force on the piston head 72 will overbalance the spring 74, and the valve 70 will leave the seat 51 and permit fluid to escape through the relieved portion 76 and hole 77 into the valve casing 54, and thence through port 69 into the tank 34. Since the maximum pressure occurs usually in the last half inch of the down stroke, this comparatively small valve will fully protect the equipment against overloading.

In some operations, it is very desirable to have a short pressure dwell on the bottom of the stroke. The safety valve arrangement may be used to accomplish this. By over-adjusting the press head somewhat downwardly, the dies will be bottomed before the plunger 11 has completed its stroke. The excess fluid of the remaining stroke will pass through the valve 70 in the manner described, and the press head 21 will dwell during this period.

The control valve as a replenishing valve

Fig. 3 shows the valve acting as a filling or replenishing valve. The spring 65 balances the sum total weight of the valves 70 and 51, sleeve 52, valve stem 71, piston head 72, washer 73, spring 74, and spring plate 53, plus the pressure in the tank 34 multiplied by the effective area of the valve 51. In the event the hydraulic system is short of oil, a vacuum will occur, and the pressure differential between the tank 34 and the fluid system will overbalance the spring 65 and move the valve 51 off its seat and permit the fluid to pass from the tank 34 into the system. As soon as the system is filled and the vacuum eliminated, the balance is restored and the spring 65 will close the valve 51 again.

The control valve as a by-pass valve for starting and stopping

Fig. 4 shows the valve acting as a by-pass valve for stopping and starting the press head.

The piston 57 of the air cylinder 56 is normally in the up position due to the constant pressure of 15 pounds per square inch maintained underneath the piston because the port 60 is connected through the pipe 78 with the upper part of the tank 34, which receives its air supply from the pipe 78 through a reducing valve 80. The safety valve 81 limits this pressure to 15 pounds per square inch. With the valve 70 closed, the hydraulic system is closed, and the reciprocating plunger 11 will cause reciprocation of the plunger 20, and the fluid will surge through the communicating pipe 19.

The drive shaft 7 at one end has keyed to it a cam 82 having a short projecting lug (Fig. 8) which actuates the operating lever 83 of a two-

way air valve 84, which is known as a "quick-as-a-wink," made by Ross Valve Mfg. Co. of Troy, New York.

One port of the valve 84 is connected by a pipe 85 with the operating valve 89, and the other port is connected by pipe 87 with pipe 79, which is connected with the port 59 of the air cylinder 56 by the branch line 88. The cam 82 is keyed to the shaft 7 in such a manner that the valve 84 is open for the instant the plunger 11 passes through the bottom of its stroke.

Manually operated air valve

The operating air valve 89 is a three-way manually operated type, and has an air supply port 90 and exhaust port 91. Placing the operating lever 92 of the valve 89 into starting position will connect the pressure supply port 90 with the port and pipe 85. The instant the plunger 11 reaches the next bottom position of the stroke and the plunger 20 with its press head 21 reaches the top position, the lug on the cam 82 will for that instant open the air valve 84 and allow air to flow through pipes 87 and 88 into the cylinder 56, thereby depressing the piston 57 and through the hollow stem 63 in the sleeve 52 open the valve 51. On the following upstroke, the displacement of the plunger 11 will pass through the valve seat 50 into the valve housing 54, valve port 69, pipe 93, and through its hole 94 into the tank 34. On the down stroke, the fluid will return from the tank in a similar manner into the cylinder 12. On subsequent strokes, the fluid will surge back and forth between the cylinder 12 and tank 34. In the meantime, plunger 20 and press head 21 remain in their upper position. By placing the operating lever 92 of valve 89 in starting position, the exhaust port 91 will be connected with the valve 84 through the pipe 85. The instant the plunger 11 reaches the next bottom position of the stroke, the lug on the cam 82 will exhaust the air pressure in the cylinder 56 through the pipes 87 and 88.

The air pressure used in this control is 70 pounds per square inch. With the air cylinder 56 exhausted, the constant air pressure of 15 pounds will immediately lift the piston 57 and with it the hollow stem 63 and cap 62. The spring 65 will close the valve 51, thereby closing the system and on the following upstroke of the plunger 11 the displacement will again pass into the cylinder 14 and cause the down stroke of the plunger 20 and the press head 21. This control can be arranged for single stroke operation or for repeat stroking. Instead of hand control, foot pedal operation may be provided.

For the purpose of inclining the press, two pedestals 94 with pivots 95, one on each side of the press, are provided. The entire press is supported by those pivots, and by means of a slide block 96 engaging lug 98 and screw 97 the press can be inclined. By inserting pins 99 in holes 100, the inclined position may be locked. Other means may obviously be used for inclining the press.

Alternative valve and pipe arrangement for auxiliary pump

Fig. 9 shows an alternative valve and pipe arrangement for use in connection with the auxiliary fluid pump 32. The pipe 35' delivers to branch pipes 101 and 102 through a piston valve 103. The branch pipe 101 is fitted with a check valve 104. A by-pass 105 connects the branch 101 above the check valve with the branch 102,

and the by-pass is fitted with the globe valve 106 and a relief valve 107.

The piston valve is shown in section in Figs. 10, 11, and 12. It includes a casing 108 having threaded nipples to receive the ends of the pipes 35', 101, and 102. It is hollow and mounted to slide therein is a piston valve 109 having heads 110 and 111 and a central bore 112 connected with ports 113 and 114.

The valve proper 109 is shifted by stems 115 and 116 equipped with knobs 117 and 118 and urged to a normal position, shown in Fig. 11, by springs 119 compressed by caps 120.

The arrows in Figs. 10, 11, and 12 indicate the flow of the fluid. With the parts in the position shown in Fig. 10, the press head will be adjusted downwardly, while with the parts in the position shown in Fig. 12, it will be adjusted upwardly; and with the parts in the position shown in Fig. 11, the output of the pump is by-passed back to the supply tank 34.

No valves impede the flow in the hydraulic system

In the invention here disclosed, the force of a single mechanically driven plunger is transmitted to a working plunger through a closed hydraulic system in which the flow is unimpeded by valves, and hence speeds up to 200 strokes per minute can be had readily, whereas prior hydraulic presses with valves in the system were limited to speeds on the order of 30 strokes per minute, because the valves retarded the operation.

In the hydraulic system of this invention, there is no valve to impede the flow between the plungers. The fluid surges back and forth freely. The valves used in the press are auxiliary, separate from the system—one, to limit the pressure to that for which the press was designed; to replenish the fluid reduced by loss; three, to control the surge to start or stop the press; and, four, to vary the volume of fluid to adjust the press.

Specific examples

By way of fuller explanation, specific figures are given, but they should not be understood as imposing unnecessary limitations.

Assuming the pull-back piston 25 of the press to be 8" in diameter and the plungers 11 and 20 6" in diameter, at 70 pounds air pressure in the pull-back cylinder 24 the pull-back force will be 3,520 pounds at the end of the upstroke and 7,040 pounds at the end of the down stroke. This force will create a hydraulic pressure on the plungers of 125 pounds per square inch minimum and 250 pounds per square inch maximum.

The safety feature or pressure relief feature of the control valve 48 is performed by the small check valve 70. As previously stated, the effective area of the lower portion or head of this valve is somewhat smaller than the area of the piston 72 carried by the upper end of the valve stem 71 and lapped into the cylinder 63. Assume the diameter of the head of the small check valve 70 to be 1" and the diameter of the piston 72 to be $\frac{1}{2}$ ", the difference in area is .1012 square inch. The passage 75 through the small check valve transmits the pressure of the hydraulic system to the cylinder 63 above the piston 72. Assume a maximum pressure desired in the system of 3500 pounds per square inch, the maximum force of the piston head pushing the valve open is the difference in area multiplied by 3500 or 354 pounds. This force is balanced by the

inner spring 74. In the event a higher pressure than 3500 pounds per square inch is generated in the system, the force on the piston head will become higher, thus overbalancing the spring and forcing the small check valve open, permitting fluid to escape from the system to the tank 34, and thereby limiting the pressure to that for which the press has been designed.

Valve 51 acting as a by-pass for starting and stopping press

Assuming the diameter of the seated part of the valve 51 to be 3" and the outside diameter of the sleeve or hollow spindle 63 to be 2½", the differential area will be 2.16 square inches.

Due to the timing valve 84, the opening and closing of the valve 51 can only take place during the up stroke of the press head or the down stroke of the eccentric. During this period, the prevailing hydraulic pressure, as previously shown, is 125 pounds minimum or 250 pounds maximum. This pressure is exerted on the under side of the valve 51 and causes a total upward pressure of 884 pounds. Counteracting is the downward force caused in the valve housing on the differential area at the prevailing tank pressure of 15 pounds per square inch, or a total of 32.4 pounds. There is an additional upward force caused by the outer spring 65 of approximately 45 pounds. The press head dwells against the adjusting nuts at the top of its stroke. During this dwell, the reaction to the hydraulic upward force is taken up by the frame of the press through the adjusting screws or sleeves 45, so that the only upward pressure against the valve 51 is the net force existing in the valve housing, which is 12.6 pounds. This is the force to be balanced by the air piston 57 on the control valve. The diameter of the piston is assumed as 5", and the air pressure is therefore .64 pounds per square inch. To this must be added the constant pressure of 15 pounds per square inch prevailing under the piston 57, which makes the required pressure for opening the valve at least 15.6 pounds per square inch. Actually, the required pressure will be somewhat less than 15.6 pounds per square inch, since the effective area of the lower face of piston 57 acted on by the tank pressure is less than the effective area of the upper face of the piston 57. Because 50 very snappy action in opening the valve is desired, a pressure of 25 pounds is used. When the air is exhausted out of the cylinder 56, the constant pressure of 15 pounds per square inch beneath the piston will raise it, and the sleeve or spindle 63 fastened to it. Since this force is 295 pounds, it is sufficient to pull this sleeve through the stuffing box. The valve 51 will be closed by the spring 65.

Valve 51 acting as a replenishing valve for keeping the system constantly filled

The outer spring 65 balances the weight of all the inner valve parts, assumed to be 9.63 pounds plus tank pressure in the valve housing of 32.4 pounds, or a total of 42 pounds. Should at any time fluid be lost from the system, a vacuum will be instantly created, which opens this valve and fills the cylinder from the tank. The instant the system is filled, the vacuum is broken and the valve closes again. This arrangement permits the sleeves 45 to be over-adjusted downwardly, producing a vacuum in the system at the top of the up stroke with the resultant slightly over filling of the hydraulic system, and the result at

the bottom of the stroke of a dwell, during which the excess hydraulic fluid of the system will be exhausted through the valve 70.

Constant gauge indication of pressure

In the conventional press, the accuracy of the adjustment depends upon the skill and judgment of the operator, and there is no way to determine readily what pressure is being exerted by the press. To overcome this difficulty, the improved press here disclosed is provided with a conveniently located hydraulic pressure gauge 150 connected with the closed hydraulic system so that the pressure per square inch can be observed directly and adjusted by the valve and pipe arrangement of the auxiliary pump.

In Fig. 1, the gauge 150 is shown connected directly to the branch pipe 31, and in Fig. 9 to the branch 105. But these are mere suggestions, and other connections will be readily made to suit particular conditions or personal preference.

I claim:

1. In a press, a work bed, a slide movable toward and away from the bed, a frame having an upright portion provided with a connecting block at its upper end, a hydraulic power-transmitting device having a driving piston and cylinder mounted on one side of said upright portion and a substantially parallel driven piston and cylinder mounted on the opposite side thereof, a fluid connection between said cylinders, an eccentric mechanical drive for the driving piston to impart substantially simple harmonic motion to such piston and through the fluid connection with the driven piston to impart similar motion to that piston, and means connecting the driven piston to the slide, said cylinders being rigidly associated with the connecting block and of such cross-sectional area and so spaced from said upright portion of the frame that the moments exerted on the connecting block by said driving and driven cylinders and pistons are substantially equal and opposite, thereby substantially eliminating bending stresses from being developed in said upright portion of the frame during the press operation.

2. A press as set forth in claim 1, including means to adjust the amount of fluid in said fluid connection, said last named means including a fluid pump and valved passageways associated therewith for enabling the pump to add to or subtract from the amount of fluid in said fluid connection.

3. A press as set forth in claim 1, in which means are provided for adjustably fixing the shut height of the driven piston, and valve means are provided in said fluid connection to automatically regulate the amount of fluid in said connection to properly accommodate the selected shut height.

4. A press as set forth in claim 1 in which means are provided to adjust the amount of fluid in said fluid connection while the press is in operation.

5. A press as set forth in claim 1 in which means are provided to adjust the amount of fluid in said fluid connection, said last named means including a valve responsive to pressure in said fluid connection for maintaining such pressure within prescribed limits.
